UNITED STATES PATENT OFFICE.

JOSEPH HERBERT CHASE, OF BUFFALO, NEW YORK, ASSIGNOR TO THE CHASE AND BAKER COMPANY, OF BUFFALO, NEW YORK.

PNEUMATIC MOTOR.

No. 852,820.

Specification of Letters Patent.

Patented May 7, 1907.

Application filed June 27, 1902. Serial No. 113,547.

To all whom it may concern:

Be it known that I, JOSEPH HERBERT CHASE, a citizen of the United States, residing at the city of Buffalo, in the county of Erie and State of New York, have invented 5 a new and useful Improvement in Pneumatic Motors, of which the following is a specification.

My invention relates more particularly to 10 motors adapted for use in piano or organ players. Motors for this purpose usually involve a plurality of bellows, a crank-shaft, suitable valve mechanism, and connections between the crank-shaft and the bellows and 15 valves. In a motor of this character, it is obviously desirable that the construction be as simple and economical of manufacture as is consistent with good practice, and as is possible without lessening the desired high 20 efficiency of the motor. This I accomplish by dispensing, as much as possible, with various parts and features heretofore considered necessary, and, in addition, I increase the 25 general efficiency by reducing friction and providing less obstructed passages for the air currents employed in operating the motor. Like the motors heretofore employed, my improved motor involves a plurality of bellows, a crank-shaft, and a valve-mechanism 30 for each bellows. But, unlike the motors heretofore employed, each valve mechanism of my improved construction includes but a single smooth-face slide-valve inclosed within a box and adapted to control both the 35 exhaust-port and the air-inlet port through which the air is alternately admitted and exhausted to and from the bellows. With this arrangement, an essential feature of the invention consists in the provision of a suction- 40 opening, whereby the exhaust acts constantly on the smooth flat face of the valve, and whereby the valve is, in this way, held to its seat by the same pressure which drives the motor. Also, with this arrangement 45 whereby a single smooth-faced slide-valve is amply sufficient for each bellows, the air passes through the valve-chamber and around the valve before entering the bellows. Furthermore, with this construction and mode 50 of operation, the ports are all on one side of the valve and all covered by the box or valve-casing. I thus provide an improved and exceedingly simplified and highly efficient mechanism for controlling the admis-

sion and exhaust of air to and from each 55 bellows.

One of the distinguishing features of my invention, and an important one, consists in the employment of a single smooth-faced slide-valve for controlling both the inlet and 60 exhaust ports, and in admitting the air to the bellows through the valve box.

Still another feature of importance consists in the employment of a suction port, which is preferably of larger area than the 65 inlet port, and which acts constantly on the smooth flat face of the slide-valve, so as to prevent the valve from becoming unseated when it moves in a direction to cover the inlet port and uncover the exhaust port. 70

These and other features, as will herein-after more fully appear, go to make up my improved motor.

My invention is illustrated in the accompanying drawing forming a part of this specification, in which:

Figure 1 is an elevation of a motor embodying my invention, showing a sectional view of portions thereof, as indicated by the cross hatching and also showing certain internal portions of said motor, indicated by dotted lines. Fig. 2 is a side elevation of such motor showing a vertical sectional view of a portion thereof, indicated by the cross hatching. Fig. 3 is a plan view of the chambered 85 block forming part of my motor.

B is a collapsible bellows, of which three are shown in Fig. 1, but that exact number is not essential to the operation of my motor, although the most convenient in practice. 90 They are all alike in construction and a side elevation of one of them is shown in Fig. 2, where b represents a side of the bellows B held immovably in position by being attached to the main frame A. The movable bellows 95 side b² is hinged or jointed to b at t and the bellows B is completed by connecting b and b² with collapsible material b⁴, such as leather or india rubber. The crank c in the crank shaft s is connected with the movable bellows 100 side b² by means of the link p. The cranks are arranged at different intervals or angles for the different bellows, the best arrangement where three bellows are employed being a crank for every 120 degrees of angular distance. A single air passage, x, connects the interior of B with the chamber v, and v in 105 turn communicates through the port o with

the exhaust passage e , and through the port o^3 with the air passage a communicating directly with the outer atmosphere; the exhaust passage e shown by dotted lines in Fig. 1, connects at E with any suitable air exhausting mechanism tending to produce a partial vacuum in e ; f is a stationary chambered block or box inclosing the chamber v ; upon the roof of f is the sliding block k moving back and forth between the guides g and g' and actuated by the revolving crank shaft s through the link p^2 ; m is a single flat slide valve moving back and forth within the chamber v and alternately opening and closing the ports o and o^3 ; the movement of the block k being communicated to the valve m by means of the pin d which plays back and forth in a narrow slot h in the roof of the chambered block f . The bottom of the slide 20 k presents a flat surface covering the slot h and prevents the ingress or egress of air to or from the chamber v through the slot. The suction opening o^2 opening into the exhaust passage e is never uncovered by the valve m , but through it a constant suction on the bottom of the valve m is exerted, thus holding the valve m securely in place and preventing any leakage of air through the ports o and o^3 when they are covered by the valve m . I 25 prefer to make the suction opening o^2 slightly larger in area of cross section than either o or o^3 , thus assuring a close fit of the valve m upon its seat without being compelled to resort to the use of a spring or other similar means.

The movements of the various moving parts of my motor are so arranged and adjusted that during the exhaustion of air from the bellows B through the passage x , the movable bellows side b^2 moves the link p which in turn imparts a rotary motion to the crank-shaft s through the crank c , the valve m , during this interval, being so placed by the link p^2 that the exhaust port o is open and the air port o^3 is closed; on the other hand, during the interval of refilling with air of the bellows B , the rotation of the crank shaft s is induced by the exhaustion of air from one or more of the other bellows B attached to the motor, 45 and the link p acted upon by the crank c forces back the bellows side b^2 and air passes into the bellows B through the opening x , the valve m being placed during this interval of refilling in such position by the link p^2 that 50 the air port o^3 is open and the exhaust port o is closed. It will be seen that a constant uniform rotation of the crank shaft is thus obtained and that from the revolving crank-shaft the power may be taken and applied by 55 any suitable means to the object desired.

It will be seen that the valve m controls both the air inlet and the exhaust ports, notwithstanding the fact that it has a smooth flat surface—that is to say, a surface devoid 60 of cavities or recesses—and that this is ac-

complished by admitting the air to the bellows through the chamber of the valve box. Furthermore, with this arrangement, the provision of the constant suction port, which is located between the air inlet and exhaust ports, and which acts constantly on the valve, prevents the latter from becoming unseated when the valve moves in a direction to close the air inlet port and uncover the exhaust port. Thus the admission and exhaust is all 70 accomplished through the medium of a single slide valve having a smooth flat face.

What I claim as my invention is:

1. In a pneumatic motor, the combination of a bellows having a single opening through which the air passes in and out, the body of the motor having an exhaust passage, a tight stationary chambered block covering the bellows opening and the exhaust passage, the chamber of said block being in constant communication with said single opening and thereby affording a passage for the admission and exhaust of air to and from the bellows, an exhaust port for connecting the said chamber with the exhaust passage, an air passage, 80 an air-inlet port for connecting the said chamber with the air passage, a single slide-valve inclosed within said chambered block, adapted to open and close the air-inlet and exhaust ports alternately, and means whereby the bellows operates said valve, said slide-valve having a flat unbroken face or working surface held in sliding contact with the flat ported valve-seat or surface upon which it works, the said slide-valve face directly controlling 85 both the admission and exhaust of air to and from the interior of the valve-chamber, and thereby controlling the admission and exhaust of air to and from the bellows.

2. In a pneumatic motor, a bellows having a single opening communicating alternately with an exhaust passage and an air-inlet passage by means of two ports opened alternately and both controlled by a single slide-valve, said slide-valve having a flat unbroken 90 face or working surface held in sliding contact with the flat ported valve-seat or surface upon which it works, the said slide-valve face alternately covering and uncovering said ports and thereby directly controlling both 95 the admission and exhaust of air to and from the interior of the valve-chamber, and thereby controlling the admission and exhaust of air to and from the bellows.

3. In a pneumatic motor, the combination of a slide-valve, a suction opening always closed by the valve and holding the latter to its seat, and a valve casing covering the slide-valve and providing a chamber in which the valve works and through which the air passes to and from the motor, said slide-valve having a flat unbroken face or working surface held in sliding contact with the flat ported valve-seat or surface upon which it works, the said slide-valve face directly controlling both 100

- the admission and exhaust of air to and from the interior of the valve-chamber, and thereby controlling the admission and exhaust of air to and from the bellows.
- 5 4. In a pneumatic motor, the combination of a bellows, admission and exhaust ports, a tight chambered block, a slide valve moving therein and connected with an outer slide by means of a pin passing through a slot in 10 the chambered block, the said slide serving to at all times keep the said slot closed, the interior of said block affording a passage for the admission of air to and from the bellows by way of admission and exhaust ports which 15 are alternately covered and uncovered and thereby directly controlled by the face of said valve, said slide-valve having a flat unbroken face or working surface held in sliding contact with the flat ported valve-seat or 20 surface upon which it works, the said slide-valve face directly controlling both the admission and exhaust of air to and from the interior of the valve-chamber, and thereby controlling the admission and exhaust of air 25 to and from the bellows.
5. In a pneumatic motor, the combination of a bellows, a tight stationary chambered block provided with and inclosing a slide-valve, the interior of said block affording a 30 passage for the admission and exhaust of air to and from the bellows, the said valve acting to open and close air-inlet and exhaust ports alternately, the said chambered block having its interior in constant communication with 35 a single opening leading to the bellows, said slide-valve having a flat unbroken face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.
- 45 6. A pneumatic motor comprising the frame or body A, the exhaust passage e, and the air-inlet passage a, the tight chambered block f attached to the said frame, the interior of said block affording a passage for the admission of air to the bellows, the slide-valve m working within the chamber of said block, the outer slide k and the pin d, the air-inlet port o³ and the exhaust port o, the bellows passage x, the suction opening o² located 50 between the air-inlet and exhaust ports and always closed by the valve, the collapsible bellows B having a movable portion b², the crank-shaft s, the crank c, and the links p and p², said slide-valve having a flat unbroken 55 face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.
- 60 65 7. A pneumatic motor comprising the stationary chambered block f providing the chamber v, the interior chamber of said block affording a passage for the admission and exhaust of air to and from the bellows, the bellows opening x, always open or uncovered, the exhaust passage e, the exhaust port o, the air-inlet passage a, the air-inlet port o³, 75 the valve m, the suction opening o² located between the air-inlet and exhaust ports and always closed by the valve, the slide k, and the pin d working in the slot h, said valve having a flat unbroken face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.

8. In a pneumatic motor, the combination of a single valve controlling air-inlet and exhaust ports communicating alternately with a single bellows opening, a suction opening located intermediate of said ports and acting to hold said valve to its seat, said slide-valve having a flat unbroken face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.
9. A pneumatic motor comprising a valve m controlling the air-inlet port and the exhaust port and always covering the intermediate suction opening o² by which it is held to its seat, said slide-valve having a flat unbroken face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.
10. A pneumatic motor comprising a motor-body having a plurality of collapsible bellows on one side thereof, tight stationary chambered inclosures on the opposite side thereof, the interior of each inclosure affording a passage for the admission of air to the bellows, a combined admission and exhaust opening leading from each bellows to and communicating constantly with the chamber of the associated inclosure, and a single slide-valve in each chamber, each valve acting to alternately make and break connection between said bellows opening and the open air, and between said bellows opening and

an air-exhausting apparatus, said slide-valve having a flat unbroken face or working surface held in sliding contact with the flat ported valve-seat or surface upon which it works, the said slide-valve face directly controlling both the admission and exhaust of air to and from the interior of the valve-chamber, and thereby controlling the admission and exhaust of air to and from the bellows.

11. In a motor, a bellows, a bellows-opening, a valve-chamber, in constant and permanent communication with said opening, admission and exhaust ports leading to and away from said chamber by which air is admitted to and exhausted from the bellows by way of said opening, and a valve in the chamber, said valve having a flat smooth unbroken face directly controlling both the ad-

mission port and exhaust port, and thereby controlling the admission and exhaust of air to and from the said valve-chamber.

12. In a pneumatic motor, the combination of the stationary chambered inclosure with the single flat smooth-faced slide-valve, there being air-inlet and exhaust ports, and there being also a suction opening intermediate of said openings, said ports being opened and closed alternately by the valve, but the said suction opening being always covered by the smooth flat face of the valve.

In witness whereof, I hereunto subscribe my name this third day of June, 1902.

JOSEPH HERBERT CHASE.
